COMBINED WATER CLOSET SEAT AND COVER

William Macowski, Jr., Caldwell, N.J., assignor to American Radiator & Standard Sanitary Corporation, New York, N.Y., a corporation of Delaware

Filed July 30, 1963, Ser. No. 76,036

Term of patent 14 years

(Cl. D4—5)

Fig. 1.

Fig. 2.

Fig. 3.

Fig. 4.

Fig. 5.

Fig. 6.

FIGURE 1 is a plan view of a combined water closet seat and cover showing my new design;

FIGURE 2 is a view in side elevation thereof;

FIGURE 3 is a view in front elevation thereof;

FIGURE 4 is a view in rear elevation thereof;

FIGURE 5 is a plan view thereof, the cover portion being omitted;

FIGURE 6 is a fragmentary sectional view thereof taken along the line 6-6 in FIG. 1 with the hardware and bolts at the rear being omitted for convenience of illustration only.

I claim:

The ornamental design for a combined water closet seat and cover, substantially as shown.
